UNITED STATES PATENT OFFICE.

JACOB P. WRIGHT, OF BARBERTON, OHIO, ASSIGNOR TO THE DIAMOND MATCH COMPANY, OF CHICAGO, ILLINOIS, A CORPORATION OF ILLINOIS.

METHOD OF AND MEANS FOR TREATING MATCH SPLINTS.

Application filed November 13, 1924. Serial No. 749,596.

To all whom it may concern:

Be it known that I, JACOB P. WRIGHT, a citizen of the United States, and resident of Barberton, in the county of Summit and State of Ohio, have invented certain new and useful Improvements in Methods of and Means for Treating Match Splints, of which the following is a specification.

This invention relates to a method of and means for treating match splints preparatory to the formation of the match heads; having reference more particularly to the treatment of splints in a continuous match making machine of the class wherein splints are cut from blocks of wood and inserted row by row into a carrier by means of which the splints are transported in spaced parallel relation through impregnating, paraffining, and head composition-applying instrumentalities.

In the cutting operation projecting fine thread-like fibres are produced on the surfaces of the splints, which fibres, when present at the free extremities of the splints, take up the match composition as the splints pass over the latter, and in consequence large imperfect heads on individual splints and also irregular head portions connecting two or more adjacent splints, are formed.

The object of my invention is to overcome the defective head formation above mentioned; and to that end the invention comprises the step of pressing the fibres, when wet, against and longitudinally of the sides of the splints, which fibres, being unresisting, cling to and remain in close contact with the splint bodies.

In carrying out my invention in a simple and efficient way I provide the impregnating solution pan, which is located beneath the path of the splint carrier, with a comb-like structure of such character as to rub the surfaces of the splints upwardly during the immersion of the splints in the liquid contents of the pan, as will be hereinafter particularly described. The precise scope of the invention will be defined in the appended claims.

In the annexed drawings—

Figure 1 is a sectional elevation of a portion of a continuous match machine equipped with combined splint impregnating and fibre rubbing means embodying the principle of my invention.

Fig. 2 is a plan, enlarged, of one end of

the impregnating pan and a cellular structure arranged therein for rubbing contact with the projecting thin surface fibres of the splints.

Fig. 3 is a transverse vertical section of a portion of the splint carrier and the underlying impregnating pan, the latter being represented in partly raised position preparatory to the engagement of its cellular structure with the depending splints on the carrier.

Fig. 4 is a side elevation of the carrier and a cross-section of the underlying pan and its contained cellular structure, said pan being represented in its normal down position.

Referring to the drawings, 5 designates a portion of an endless travelling carrier into which the upper ends of succeeding rows of splints are inserted as rapidly as they are cut from a block of wood at the cutting and setting station of a match machine, which carrier transports the splints through the match-making cycle, including the impregnating pan 6 which precedes the usual drier, 80 the paraffin bath and the head composition applying mechanism.

The pan 6 contains a solution of material, such as ammonium phosphate, into which the depending splints on the carrier are immersed, which solution impregnates the individual splints and is adapted to prevent their after-glow when the splints, as complete matches, are ignited and the flame extinguished. The wet splints as they progress through the drier are dried preparatory to their dipping in the paraffin bath, from which latter the splints pass to and through the head-composition on the usual composition-applying roller or rollers.

The splint carrier 5 herein illustrated comprises a continuously moving chain of hingedly connected plates having rows of perforations therein adapted to receive and hold the upper ends of the match splints; 100 and the pan 6, which is located beneath the path of the carrier, has the capacity of receiving at one time the groups of splints depending from two adjacent carrier plates. In the present instance this pan has a four-way motion in timed relation to the continuous travel of the carrier; that is to say, the pan has an upward movement toward the carrier, a horizontal and downward movement concurrently with the travel of 110

- the carrier, and a return horizontal movement to the normal or starting position, the downward movement of the pan being slow as compared with its upward movement.
- 5 In this way the splints in each succeeding pair of plates are immersed in and effectually treated with the liquid contents of the pan. The pan, which is vertically guided in a horizontally-movable bed 7, is flexibly suspended by links 8 from rocker-arms 9 that are actuated by means of a suitable cam 10 to effect a rising and falling motion of the pan. The bed, which is supported and guided in a drip pan 10', is connected by means of links 11 to arms 12 depending from a shaft 13 having an arm 14 under the influence of a suitable cam 15 which operates to impart to the bed and pan a reciprocatory motion longitudinally of the carrier. No claim is made by me to the specific impregnating mechanism described.
- In pursuance of my invention, I confine within the pan 6 a rectangular frame structure 16 having rows of elongated vertical cells 17 corresponding in number and position with the splint receiving perforations of two adjacent carrier plates; so that when the pan is raised the cells receive the respective splints depending from the plates. The cells are preferably square in cross-section and are each of an area to permit their sliding reception of the respective splints. The walls of the cells, thus exerting an extended rubbing effect on the surfaces of the splints during the elevation of the pan, press the projecting wet fibres of the splints upward and longitudinally against the bodies of the splints. The fibres naturally remain in this position, and in consequence the formation of imperfect heads on the splints when they pass through the composition on the composition roller is obviated, as previously mentioned. The mouths of the cells are preferably outwardly beveled, as at 18, to provide inclined surfaces which contact with the lower ends of splints that may happen to be slightly out of vertical alignment with the respective cells, thus straightening the misplaced splints and ensuring their uniform passage through the head composition.

It is to be understood that I do not limit my invention to the particular construction herein disclosed, as the mechanism may be modified within the principle of my invention and the scope of the appended claims.

I claim—

1. A process of making matches having wood splints, comprising wetting the splints

and, while wet, pressing their projecting fine surface fibres against the bodies of the respective splints.

2. A process of making matches having wood splints, comprising immersing the splints in an impregnating liquid and at the same time pressing their projecting fine surface fibres against and longitudinally of the bodies of the respective splints.

3. In a match making machine of the class described having a splint carrier, and means for treating the splints borne by the carrier with an impregnating liquid, means for pressing the projecting fine surface fibres of the wet impregnated splints against and longitudinally of the bodies of the respective splints.

4. In a match making machine of the class described having a splint carrier, and means for treating the splints borne by the carrier with an impregnating liquid, means for pressing the projecting fine surface fibres of the splints against and longitudinally of the bodies of the respective splints during the immersion of the splints in the impregnating liquid.

5. In a match making machine of the class described having a splint carrier, a pan adapted to contain impregnating liquid, and means for effecting a relative movement between the carrier and the pan whereby the splints borne by the carrier are immersed in and separated from the liquid contents of the pan, a cellular structure in said pan formed and positioned to receive the respective splints during the relative immersing movement and at the same time to push the projecting fine surface fibres of the splints upwardly and longitudinally of the bodies of the splints.

6. In a match making machine of the class described having a splint carrier, a pan adapted to contain impregnating liquid, and means for effecting a relative movement between the carrier and pan whereby the splints borne by the carrier are immersed in and separated from the liquid contents of the pan, a frame structure located within the pan and having rows of elongated vertical cells of such cross-sectional area as to receive the respective splints during the relative immersing movement and at the same time to push the projecting fine surface fibres of the splints upwardly and longitudinally of the bodies of the splints.

Signed at Barberton, in the county of Summit and State of Ohio this 4 day of November A. D. 1924.

JACOB P. WRIGHT.
